ABSTRACT OF THE DISCLOSURE

This invention is concerned with a particular construction of rivet employed in securing draw die beads to the surface of draw dies and to the combination of the draw die, the draw die bead and the draw die bead steel fastening pin.

BACKGROUND OF THE INVENTION

Draw dies are widely used in the fabrication of sheet metal parts which must be produced in large volume. These draw dies are routinely provided with draw die beads which are so located as to secure the sheet metal being drawn firmly between the cooperating dies while the draw is being made so that the metal cannot flow except in the direction for which the dies have been designed and constructed. The use of such draw die beads is conventional and shall not further be described.

The means used to secure the draw die beads to the draw dies have in the past been far from satisfactory. Such fastening means must be cheap, reliable and totally resistant to the high mechanical stresses incident to operation and to the thermal stresses sometimes encountered in the local heat treatment of the dies. This invention is addressed to the provision of such a fastening means and the cooperating draw die and draw die bead.

2

DESCRIPTION OF THE INVENTION

This invention is best understood in conjunction with the drawings in which:

FIGURE 1 is a view of the draw die bead steel fastening pin upon which this invention is predicated; and

FIGURE 2 is an enlarged section of a portion of the serrations shown in gross in FIGURE 1; and

FIGURE 3 is a cross section taken through the serrated portion of the draw bead steel fastening pin showing the air escape groove; and

FIGURE 4 is a cross section of a portion of the draw die, the draw die bead and the draw die bead rivet taken normal to the axis of the draw die bead.

The draw die bead steel fastening pin depicted in FIGURE 1 has been fabricated from SAE 1045 steel to take advantage of the economy and ready hardenability of this steel. One end of this rivet is serrated as shown in FIGURE 1 in gross and in detail in FIGURE 2. This serrated portion is 0.75 inch (1.91 cm.) long. The diameter of the teeth of the serrations is from 0.200 to 0.198 inch (0.508 to 0.503 cm.) and the diameter of the base of the serrations is from 0.180 to 0.177 inch (0.456 to 0.450 cm.). A cylindrical section 0.125 inch (0.317 cm.) long separates the serrated portion from the tapered end portion. It is preferred that elements of the truncated cone represented by this tapered portion include an angle of about four degrees although under some circumstances this taper may be replaced by a straight cylinder.

This draw die steel fastening pin is received in coaxial holes in the draw die and the draw die bead. The diameter of the hole in the draw die should be about 0.191 inch (0.485 cm.). The diameter of the coaxial hole in the draw die bead should be large enough to permit passage therethrough of the serrated portion of the draw die steel fastening pin and to interfere with the tapered portion. A suitable diameter has been found to be 0.203 inch (0.516 cm.). The draw die bead steel fastening pin is hardened in the portion in contact with the draw die and less hard in the portion in contact with the draw die bead.

The following tabulation is presented to demonstrate the results obtained with this type of fastening between a draw die and the draw die bead.

1.....	Present standard draw bead steel fastening pin in .1865" diameter holes.	1,730 pounds.
2.....	Present standard draw bead steel fastening pin in .1865" diameter holes, epoxy glued.	1,760 pounds.
3.....	.200" O.D. knurled draw bead steel fastening pin in .191" diameter holes.	1,035 pounds.
4.....	.200" O.D. knurled draw bead steel fastening pin in .191" holes, epoxy glued.	2,450 pounds.
5.....	.200" O.D. draw bead steel fastening pin with circular teeth in .191" diameter holes.	4,610 pounds broke bead, one draw bead steel fastening pin, pulled up.
6.....	.200" O.D. draw bead steel fastening pin with circular teeth in .191" diameter holes.	3,650 pounds broke one draw bead steel fastening pin and bead.
7.....	.200" O.D. draw bead steel fastening pin with circular teeth in .193-.195" diameter holes.	1,500 pounds draw bead steel fastening pins pulled out of hole.
8.....	.200" O.D. draw bead steel fastening pin with circular teeth in .190" diameter holes.	1,340 pounds draw bead steel fastening pins pulled out of hole.
9.....	.200" O.D. draw bead steel fastening pin with circular teeth, tapered head so no peening needed in .195-.196" diameter holes.	1,750 pounds draw bead steel fastening pins pulled out of holes.

We claim as our invention:

1. A draw die and a draw die bead securely fastened together, said draw die bead and said draw die having coaxial openings for the reception of a draw die bead steel fastening pin and a draw die bead steel fastening pin occupying such openings, said draw die bead steel fastening pin being hardened in the portion in contact with the draw die and being less hard in the portion in contact with the draw die bead, said hardened portion of the draw die bead steel fastening pin being serrated and in which the serrations are constructed to favor penetration of the draw die bead steel fastening pin into the draw die and to oppose the withdrawal of the draw die bead steel fastening pin, the upper end of the draw die bead steel fastening pin being no higher than flush with the draw die bead.

2. The structure recited in claim 1 in which the portion of the draw die bead steel fastening pin in engagement with the draw die bead is tapered with the lesser end of the taper adjacent the draw die.
